UNITED STATES PATENT OFFICE.

FRANK A. LUNDBERG, OF CHICAGO, ILLINOIS, ASSIGNEE TO TELEGRAPHIC EQUIPMENT COMPANY, INCORPORATED, OF NEW YORK, N. Y., A CORPORATION OF NEW YORK.

AUTOMATIC SWITCH.

1,287,716.

Specification of Letters Patent. Registered Dec. 11, 1918.

Application filed April 12, 1917. Serial No. 169,814.

To all whom it may concern:

Be it known that I, FRANK A. LUNDBERG, a citizen of the United States, residing at Chicago, in the county of Cook and State of Illinois, have invented certain new and useful Improvements in Automatic Switches, of which the following is a full, clear, concise, and exact description.

This invention relates to automatic switches of the type employed in telephone exchange systems, and has for its object the provision of a switch of new and improved construction which shall rapidly select a desired line.

15 A feature of the invention is the provision of a switch which shall move its brush continuously over groups containing non-desired lines, and which shall, upon reaching a desired group, step its brush to a desired line in the group.

More specifically, a brush shaft, slidably mounted in a support, is moved through said support until the brush reaches a desired group of lines, at which time the shaft comes 25 to rest with respect to the support, and the support itself is moved so as to step the brush to the desired line in the selected group.

The accompanying drawing shows diagrammatically a line switch embodying the principles of the invention, with that portion of the operating circuits which is necessary to an understanding of the operation of said switch.

35 The brush shaft 1 is slidably mounted in a support 3 and carries wipers 2 and 41 which cooperate with the terminal bank 4. Only the test brush 2 has been shown in its operative relation with the test terminals 40 to avoid complicating the drawing. The terminals 4 are divided into groups, which may contain any suitable number of lines, five lines being shown in each group in the drawing. The shaft 1 is retained in its position 45 with respect to the support 3 by the engagement of a pawl 6, carried by said support, with one of the notches 7 cut in the shaft 1.

These notches 7 are spaced so as to correspond with the groups of terminals referred 50 to. A magnet 8 is provided to control the selection of a group of lines and operates when energized to remove the pawl 6 from engagement with the notches 7, whereupon the shaft 1 falls under the attraction of 55 gravity, or is moved downward by the action

of spring 33 upon pulley 35, which is loosely mounted on a shaft 34, at which time the flexible cord 39 will be wound upon the pulley 35.

Selection of individual lines in a selected group is accomplished by stepping the support 3 in a downward direction under the control of the escapement 15 and the ratchet 5. Upon each energization of magnet 14 support 3 is lowered a distance equal to one-half the distance between adjacent line terminals so that the brushes will move from one terminal to the next only after the deenergization of the magnet 14. Upon the first energization of the magnet 14 support 3 and shaft 1 will move down one-half step, causing the closure of contacts 16 and 17. In this position a block of insulation 21, carried on shaft 1, will also close contact springs 22, 23. The insulation 21 is made long 75 enough to close springs 22', 23', associated with the second group of lines, just prior to the opening of springs 22, 23, during the downward travel of the brush shaft, and so on for succeeding groups. A side switch, of 80 which wipers 39 and 40 are shown, is controlled by an escape magnet 12 so that, upon the first energization of this magnet, the wipers move to position 2 and upon the first deenergization move to position 3. 85

The invention will be more clearly understood from a consideration of the following description of the operation of the switch.

When the subscriber at substation A removes his receiver from the hook, a circuit 90 is completed for energizing line relay 37 from grounded battery, left-hand winding of relay 37, outer armature and contact of relay 38, through the substation, contact and inner armature of relay 38, through the 95 right-hand winding of relay 37 to ground. A circuit is thereupon completed from grounded battery, armature and contact of relay 37, conductor 36, side-switch wiper 40 (position 1), winding of side-switch escape 100 magnet 12, through the winding of the relay 14 to ground. The magnets 12 and 14 are energized in this circuit, magnet 12 causing the side switch to move into position 2, and magnet 14 releasing the support 3 downward 105 one-half step, and closing contact springs 19 and 20.

Busy lines are indicated by the presence of battery potential on the test contact 4 and by the energized condition of the relay 1.

25, individual to the tested line, which energization is caused in a manner to be described. If all the lines in the first group are busy, a circuit will now be completed 5 from ground 24, through the front contacts and armatures of relays 25", 25", 25", 25", 25, springs 22, 23, winding of magnet 8, springs 20, 19 to battery and ground. The magnet 8, being energized in this circuit, 10 closes contact springs 26, 27 and releases brush shaft 1. The circuit for magnet 8 will be maintained until a group of lines, one or more of which is idle, is found. When such a group is encountered this circuit 15 will be broken at the contact of a relay 25, associated with the idle line, and magnet 8 will deenergize, arresting the travel of the shaft 1 with test wiper 2 one-half step above the contact of the first line in the selected group.

During the fall of brush shaft 1, the magnets 12 and 14 are held energized over a circuit from grounded battery, springs 27, 26, springs 17, 16, shaft 1, conductor 28, 25, wiper 40 (position 2), through the windings of magnets 12 and 14 to ground. Upon the deenergization of magnet 8 this circuit is broken by the opening of springs 26, 27 and magnet 14 deenergizes, but magnet 12, being 30 slow to release, is maintained energized until the wiper 2 has been brought into contact with the test terminal of the first line in the group by the deenergization of magnet 14. Should this line be busy, a circuit would be 35 completed from battery, found on the test terminal, shaft 1, conductor 28, wiper 40 (position 2), through the windings of magnets 12 and 14 to ground. Magnet 14 would be again energized, stepping the wiper 2 40 half-way to the next terminal, and interrupting its circuit so that, upon deenergization, the wiper 2 would be brought into contact with said terminal. So long as busy terminals are encountered, the wiper 2 is 45 stepped in this way by the action of the magnet 14 until an idle line is reached, at which time, no battery potential being found 50 on the test terminal, magnet 14 remains deenergized, and magnet 12 deenergizes and moves wipers 39 and 40 into position 3.

In this position of the side switch a circuit is completed from grounded battery, through winding of the cut-off relay 38, wiper 39 (position 3), conductor 28, brush 55 shaft 1, wiper 2, selected terminal 4, winding of relay 25 to ground. Both relays 38 and 25 attract their armatures in this cir-

cuit, but their resistances are adjusted so that battery potential will predominate on the contact 4 of the selected line and its multiples before other switches, thus denoting the busy condition of the selected line. The brushes 41 now rest on the terminals of an idle line which may lead either to a selector switch or an operator, and the subscriber 60 65 may now complete his connection in the usual manner.

What is claimed is:

1. In an automatic switch, a brush shaft, a brush on said shaft, a series of contacts 70 arranged in alinement and divided into groups arranged to be engaged by said brush, a supporting member, means for moving said shaft relative to said supporting member to move said brush from one group 75 of contacts to another, and means for moving said support to move said brush from contact to contact in a group.

2. In an automatic switch, a shaft, a brush carried thereby, a series of contacts 80 arranged in alinement and divided into groups arranged to be engaged by said brush, a support in which said shaft is longitudinally movable, means for moving said shaft 85 relative to said support to move said brush from group to group of said contacts, and means for moving said support to move said brush from contact to contact in a group.

3. In an automatic switch, a shaft, a brush carried thereon, a series of contacts 90 divided into groups arranged to be engaged by said brush, a support on which said shaft is longitudinally movable, ratchet teeth on said shaft corresponding to said groups of contacts, a pawl for engaging said ratchet 95 teeth, a magnet for retracting said pawl to permit said shaft to move relatively to said support, whereby said brush will move from group to group of said contacts, means for releasing said support, and means for thereupon controlling the movement of said support to move said brush from contact to contact in a selected group.

4. In an automatic switch, a shaft movable only in a longitudinal direction, a brush carried thereby, a support in which said shaft is movable, means for moving said shaft relative to said support and means for moving said support and shaft together in a longitudinal direction.

In witness whereof, I hereunto subscribe my name this 16th day of April, A. D. 1917.

FRANK A. LUNDQUIST.
